ATTACHMENT FOR STITCH FORMING
MECHANISMS OF SEWING MACHINESCharles T. Gould and Herbert M. Bonney,
Walpole, Mass.

Application June 21, 1937, Serial No. 149,288

14 Claims. (Cl. 112—2)

This invention relates to sewing machines and particularly to a sewing machine designed to stitch together the opposite walls of a pad containing fluffy material to expand when pressure is removed therefrom.

The object of the invention is to form elongated loops in the stitches as formed, the length of these loops being sufficient to take care of the subsequent expansion of the pad.

10 The invention consists primarily in the combination of a reciprocating thread-pulling blade coacting with a holding member consisting of two plates riveted together and separated at the end nearest the needle, whereby in the forward movement of the pulling blade said blade moves over the holding member, seizes the thread and on its return movement pulls a loop of thread between said two plates which retain the loop thus formed in position until the next stitch is 20 formed.

For the purpose of illustrating the invention, one preferred form thereof is illustrated in the drawing, this form having been found to give satisfactory and reliable results, although it is 25 to be understood that the various instrumentalities of which the invention consists can be variously arranged and organized, and the invention is not limited to the precise arrangement and organization of these instrumentalities as herein shown and described except as required by the 30 scope of the appended claims.

Of the drawing—

Figure 1 represents a vertical section of a portion of a sewing machine adapted to sew together the opposite separated walls of a pad containing fluffy material and showing mechanism embodying the present invention, said mechanism showing the loop of thread clamped between the two plates of a loop-holding member.

40 Figure 2 represents a similar vertical section showing the hooked thread-pulling blade in position to seize the thread and draw it into a position to be clamped by the holding member.

Figure 3 represents a partial plan showing a 45 portion of the presser foot, the loop-holding member mounted thereon, and a portion of the reciprocating hooked thread-pulling member in position to be moved forward in the direction of the arrow *a* to seize the thread.

50 Figure 4 represents a similar view showing the hooked pulling member moved back in the direction of the arrow *b* and drawing a loop of thread between the two thicknesses of the loop-holding member.

55 Figure 5 represents a similar view showing the

hooked thread-pulling member moved to the end of its rear movement and with the loop of thread clamped between the two plates of the loop-holding member, this view showing in dotted lines the position of said hooked pulling member on its forward movement in the direction of the arrow *c* as it is about to pass over the loop-holding member and 5

Figure 6 represents a section on line 6, 6 on Fig. 4. 10

Similar characters indicate like parts throughout the several figures of the drawing.

In the drawing, 10 represents a bed plate of a sewing machine supporting a pad 11 containing a considerable thickness of fluffy material, said 15 pad being adapted to be moved over the surface of the bed plate by any suitable mechanism to the right of said figure.

The sewing machine has a reciprocating and oscillating needle 12 and a looper 13, said needle 20 and looper being actuated in any well known manner.

The sewing machine also has a presser foot 14 bearing upon the top of the pad 11 and keeping the pad under compression while stitches 25 are being formed therein by said needle 12 and looper 13.

Positioned near one end of the presser foot 14 is a disk 15 mounted upon a shaft 16 having secured to one end thereof a lever 17 to the 30 outer end of which is pivoted a reciprocating member 18.

The member 18 may be reciprocated in any well known manner from a crank forming a part of the sewing machine and during the reciprocation 35 of the member 18 it imparts a 90° oscillating movement to the disk 15.

Secured at 19 to the periphery of the disk 15 is a resilient thread-pulling blade 20, the forward 40 end of which rests upon the upper face of the presser foot 14.

The forward end of the thread-pulling blade 20 is slightly bent upwardly at 21 and is provided with a laterally extending hook 22.

The presser foot 14 is provided with a plurality of elongated openings 23, said openings being parallel to each other and through one of which the needle 12 is adapted to pass and then through the pad 11 to coact with the looper 13 and form 50 the required stitch.

Beneath the presser foot 14 is a block 24 having an elongated rib 25 positioned in another of the openings 23.

Screws 26 threaded to the block 24 extend 55

through notches 27 in a loop-holding member consisting of two thin metal plates 28 and 29, riveted together at 29x, the plate 28 being superimposed upon the plate 29 and being preferably 5 of slightly increased thickness.

These plates 28 and 29 have rearward extensions 30 projecting beyond the hook 22 of the reciprocating thread-pulling blade 20.

As shown in Fig. 3 the upper left hand corner 10 of the extension 30 of the plate 28 is slightly bent upwardly as at 31.

The extension 30 of the lower plate 29 has its upper left hand corner slightly inclined downwardly as indicated at 32 in Fig. 2 of the drawing.

15 When the thread-pulling blade 20 is moved forwardly from the position indicated in Fig. 1 of the drawing, the extreme forward end 33 thereof will pass over the rearward extension 30 of the holding plate 28 into the position indicated 20 in Fig. 2 of the drawing, at which point the hook 22 thereof will be in position to seize the thread 34 extending downwardly from the needle 12 to the looper 13. It is obvious that the movement of the needle 12 must have such timed relationship 25 to the movement of the blade 20 that the needle 12 will be in its upper position after coacting with looper 13 to form a loop 35 so that on the return movement of the blade the hook 22 will engage the thread and draw out the loop 35 and elongate 30 it as shown in the drawing.

On the return movement of the thread-pulling blade 20 the hook 22 will engage with the inclined portions 31 and 32 of the plates 28 and 29 and will be drawn between these plates 28 and 29 carrying 35 with it the loop 35 as indicated in Figs. 4 and 5 of the drawing.

The loop 35 at this time will be gripped between the plates 28 and 29 and remain thus gripped when the thread-pulling blade 20 moves forward 40 in the direction of the arrow c on Fig. 5, this forward movement of the blade 20 being in a direction opposite to the rearward movement of the work being operated upon during the stitch forming operation.

45 As soon as the hook 22 disengages from the loop 35 the loop will drop sufficiently to permit the forward end 33 of the thread-pulling blade 20 to pass over the upper plate 28 as indicated in Fig. 3 of the drawing.

50 As the pad 11 is moved toward the rear of the sewing machine preparatory to the formation of another stitch therein it will pull the loop 35 from between the plates 28 and 29 and said loop will be carried along with the said pad 11 leaving the 55 plates 28 and 29 free to receive another loop upon the return movement of the thread-pulling member 20.

This thread-pulling member 20 is of spring metal and has sufficient tension to retain it substantially in contact with the upper face of the curved presser foot 14 during its reciprocation.

60 By means of the mechanism herein shown an elongated loop may be formed in the formation of each stitch, the length of the loop being sufficient to take care of the expansion of the pad as it moves away from the stitch-forming mechanism.

65 By means of the screws 26 and notches 27 the loop-holding plates 28 and 29 may be adjusted 70 toward and from the thread-pulling blade 20 until said plates and blade are properly positioned relatively to each other.

The presser foot 14 has a length greater than the width of the pad 11 being operated upon and 75 a plurality of stitch-forming mechanisms are em-

ployed in connection with the presser foot in order that a plurality of rows of stitches may be formed simultaneously in the pad 11.

By having a plurality of openings 23 in the presser foot 14 the loop-holding devices may be 5 disposed in any desired openings 23 to vary the spaces between the rows of stitches, it being understood that the other mechanisms coacting with said loop-holding devices must receive similar adjustments.

This feature, however, forms no part of the present invention and consequently it is deemed unnecessary to illustrate the same in detail.

The present invention relates wholly to the 15 novel means whereby elongated loops of thread may be formed during the formation of the stitches and whereby each loop is released prior to the formation of the next stitch.

It must be understood that the needle 12 not only reciprocates up and down but while in the 20 material being operated upon it is adapted to oscillate, traveling with the material until it leaves said material when it is moved forward to its original position preparatory to the formation of another stitch.

This oscillation of the needle is effected by means of a small eccentric.

This oscillation of the needle is necessary as the material being sewed is so heavy that it cannot be stopped and started as each stitch is 30 formed.

While in the material the needle swings with said material in the direction said material is traveling and it will swing in the opposite direction when it has left the material in its upward 35 movement.

It is believed that the operation and many advantages of the invention will be understood readily without further description.

Having described our invention, we claim:

1. In a sewing machine for stitching together the opposite walls of a pad containing a thick layer of fluffy material and having two cooperating stitch forming devices, a mechanism consisting of a flat reciprocating blade provided at 45 its forward end with a lateral hook to seize the thread at a point between said devices; means for moving said blade rearwardly to form an elongated loop in said thread; a work support; a presser foot above said support; and independent means secured to the upper face of said presser foot for gripping said loop until the next forward movement of said blade.

2. In a sewing machine for stitching together the opposite walls of a pad containing a thick 55 layer of fluffy material and having two cooperating stitch forming devices, a mechanism consisting of a flat reciprocating blade provided at its forward end with a lateral hook to seize the thread at a point between said devices; means for moving said blade rearwardly to form an elongated loop in said thread; a work support; a presser foot above said support; and coacting flat spring jaws secured to the upper face of said presser foot for gripping said loop until the next 60 forward movement of said blade.

3. In a sewing machine for stitching together the opposite walls of a pad containing a thick 70 layer of fluffy material and having two cooperating stitch forming devices, a mechanism consisting of a work support; a curved presser foot above said support; a flat reciprocating blade of spring metal provided at its forward end with a hook to seize the thread at a point between said devices, said blade being movable forwardly over 75

the upper face of said presser foot; means for moving said blade rearwardly to form an elongated loop in said thread; and independent means secured to the upper face of said presser foot for gripping said loop until the next forward movement of said blade.

4. In a sewing machine for stitching together the opposite walls of a pad containing a thick layer of fluffy material and having two cooperating stitch forming devices, a mechanism consisting of a flat flexible reciprocating blade provided at its forward end with a lateral hook to seize the thread at a point between said devices, said hook being integral with said blade; means for moving said blade rearwardly to form an elongated loop in said thread; a work support; a presser foot above said support; and independent means secured to the upper face of said presser foot for gripping said loop until the next forward movement of said blade.

5. In a sewing machine for stitching together the opposite walls of a pad containing a thick layer of fluffy material and having two cooperating stitch forming devices, a mechanism consisting of a flat reciprocating blade provided at its forward end with a lateral hook to seize the thread at a point between said devices; means for moving said blade rearwardly to form an elongated loop in said thread; a work support; a presser foot above said support; and independent means secured to said presser foot for gripping said loop until the next forward movement of said blade, said loop gripping means being adjustable toward and from said hook.

6. In a sewing machine for stitching together the opposite walls of a pad containing a thick layer of fluffy material and having two cooperating stitch forming devices, a mechanism consisting of a flat reciprocating blade provided at its forward end with a lateral hook to seize the thread at a point between said devices; means for moving said blade rearwardly to form an elongated loop in said thread; a work support; a presser foot above said support; and means mounted on said presser foot and extending over an intermediate part of said elongated loop and gripping the same.

7. In a sewing machine for stitching together the opposite walls of a pad containing a thick layer of fluffy material and having two cooperating stitch forming devices, a mechanism consisting of a flat reciprocating blade provided at its forward end with a lateral hook to seize the thread at a point between said devices; means for moving said blade rearwardly to form an elongated loop in said thread; a work support; a presser foot above said support; and two thin plates riveted together and between which said loop is drawn by said blade for temporarily gripping said loop until the next forward movement of said blade, said plates being mounted on said presser foot and adjustable toward and from said blade.

8. In a sewing machine for stitching together the opposite walls of a pad containing a thick layer of fluffy material and having two cooperating stitch forming devices, a mechanism consisting of a flat reciprocating blade provided at its forward end with a lateral hook to seize the thread at a point between said devices; means for moving said blade rearwardly to form an elongated loop in said thread; a work support; a presser foot above said support; and independent means comprising plates secured to said presser foot for gripping said loop until the next

forward movement of said blade, said plates at their forward ends having oppositely disposed inclined faces at a corner thereof forming a mouth to receive the hook in its rearward movement.

9. In a sewing machine for stitching together the opposite walls of a pad containing a thick layer of fluffy material and having two cooperating stitch forming devices, a mechanism consisting of a flat reciprocating blade of spring metal provided at its forward end with a lateral hook to seize the thread between said devices; an oscillating disk to which the rear end of said blade is secured; means for actuating said disk to move said blade endwise in a forward direction and to move it rearwardly to form an elongated loop in said thread; a work support; a presser foot above said support; and independent means secured to said presser foot for gripping said elongated loop until the next forward movement of said blade.

10. In a sewing machine for stitching together the opposite walls of a pad containing a thick layer of fluffy material and having two cooperating stitch forming devices, a mechanism consisting of a flexible flat reciprocating blade having its forward end elevated above the body of the blade and provided with a lateral hook to seize the thread at a point between said devices; means for moving said blade rearwardly to form an elongated loop in said thread; a work support; a presser foot above said support; independent means secured to said presser foot for gripping said loop until the next forward movement of said blade; and means for moving said blade forward over the top of said loop gripping means.

11. In a sewing machine for stitching together the opposite walls of a pad containing a thick layer of fluffy material and having two cooperating stitch forming devices, a mechanism consisting of a flexible flat reciprocating blade having its forward end elevated above the body of the blade and provided with a lateral hook to seize the thread at a point between said devices; means for moving said blade rearwardly to form an elongated loop in said thread; a work support; a presser foot above said support; means mounted on said presser foot and having rear extensions between which said elongated loop is adapted to be gripped; and means for moving said blade forwardly over the top of said gripping extensions thereby releasing the hook from said loop.

12. In a sewing machine for stitching together the opposite walls of a pad containing a thick layer of fluffy material and having two cooperating stitch forming devices, a mechanism consisting of a flexible flat reciprocating blade having its forward end elevated above the body of the blade and provided with a lateral hook to seize the thread at a point between said devices; means for moving said blade rearwardly to form an elongated loop in said thread; a work support; a presser foot above said support; two thin plates riveted together and between which said loop is drawn by said blade for temporarily gripping said loop until the next forward movement of said blade; and means for moving said blade forwardly over the top of said plates and releasing the loop from said hook.

13. In a sewing machine for stitching together the opposite walls of a pad containing a thick layer of fluffy material and having two cooperating stitch forming devices, a mechanism consisting of a flexible flat reciprocating blade having its forward end elevated above the body of the blade

- and provided with a lateral hook to seize the thread at a point between said devices; means for moving said blade rearwardly to form an elongated loop in said thread; a work support; a
5 presser foot above said support; independent means comprising plates secured to said presser foot for gripping an intermediate portion of said loop until the next forward movement of said blade, said plates at their forward ends having
10 oppositely disposed inclined faces at a corner thereof forming a mouth to receive the hook in its rearward movement; and means whereby said blade in its forward movement will pass over the top of said gripping means.
15 14. In a sewing machine for stitching together the opposite walls of a pad containing a thick layer of fluffy material and having two cooperat-

ing stitch forming devices, a mechanism consisting of a flat reciprocating blade of spring metal provided at its forward end with a hook to seize the thread at a point between said devices; an oscillating disk to which the rear end of said blade is secured; means for actuating said disk to move said blade rearwardly to form an elongated loop in said thread; a work support; a presser foot above said support; and independent means secured to said presser foot for gripping intermediate portions of said elongated loop until the next forward movement of said blade, and means whereby in the forward movement of said blade it will pass over the top of said gripping means.
